MULTIZERO INDEXING DEVICE FOR ADDING MACHINES

Filed Dec. 15, 1950

UNITED STATES PATENT OFFICE

2,647,690

MULTIZERO INDEXING DEVICE FOR
ADDING MACHINESWalter A. Anderson, Bridgeport, Conn., assignor
to Underwood Corporation, New York, N. Y., a
corporation of Delaware

Application December 15, 1950, Serial No. 201,031

5 Claims. (Cl. 235—63)

1

This invention relates to indexing means for ten key adding machines and more particularly to a mechanism for indexing a plurality of zeros by a single key depression.

The copending application of O. W. Swanson and E. O. Mossberg, Serial No. 182,672, filed September 1, 1950, discloses a printing calculating machine in which a constant factor may be stored for multiplication purposes. In the machine of that application a constant factor is entered by indexing the factor itself and then individually indexing a number of zeros sufficient to shift the indexed factor into alignment with the highest denominational order type bars. The present machine is designed to eliminate the need for repeated operation of the zero key in such a printing calculating machine when a constant factor is to be indexed.

It is accordingly an object of this invention to provide in an adding machine having a ten key indexing mechanism, means to index a plurality of ciphers at a single operation.

It is another object of this invention to disclose a mechanism settable by depression of a key to thereafter index a zero in all denominational orders brought within setting range of the mechanism.

A still further object is to provide a mechanism settable by a key to a zero indexing position and a cooperating mechanism also key-operated, to relatively move the zero indexing mechanism and the indexable means to index a plurality of zeros in the indexable means.

Another object is to provide mechanism operable to a zero indexing position and in cooperation with a constant entering key, operable to index a zero in all unindexed denominational orders.

Still another object is the provision of a multi-zero indexing device operable to index zeros in a variable number of denominational orders.

Other objects will be in part obvious and in part specifically pointed out in the following description of a preferred embodiment of the invention.

In the accompanying drawings—

Figure 1 is a perspective showing of the zero indexing device.

Figure 2 is a plan view of the zero indexing device and the constant key mechanism, and

Figure 3 is a detail view of the zero indexing mechanism detent of Figure 1.

General operation

The disclosed zero indexing device is an improvement in the printing calculating machine

2

disclosed in the application of O. J. Sundstrand, Serial No. 170,968, filed June 29, 1950, and the above noted Swanson et al. application. In the following description, only so much of the mechanism of these applications shall be described as is necessary to set out the features of the present invention.

It will be remembered that when a constant factor is to be indexed in the machine of the 10 Swanson et al. application, the operator must first index the significant digits of the constant and then index a number of zeros sufficient to shift the constant to the highest denominational orders. The present structure is designed to 15 index all denominational orders remaining after the significant constant digits have been indexed by the operation of a zero indexing key and release of the indexing mechanism for movement to its fully indexed position. During such movement, a zero is indexed in each order as it moves relatively past the key-operated setting means.

The constant factor mechanism

The indexing mechanism of the present disclosure is the same as that of the well known "Underwood Sundstrand" adding machines and will be but briefly described. A field of settable pins 11 are mounted in a stationary frame 12 and when set to an effective position will control the movement of the usual register entering mechanism, indicated at 9, Figure 2. These pins 11 are selectively settable to an active position by a plurality of push rods 13 which are mounted for sliding movement on a swinging arm 15 pivoted at 16 on the keyboard base plate 17.

A spring 20 coiled between a plate 21 fixed to arm 15 and a stud 22 on the forward portion of plate 17 tensions arms 15 for clockwise movement in Figure 2 to shift the push rods 13 across the field of stops 11. Push rods 13 are normally retained in alignment with the leftmost line of pins 11 by a toothed escapement arm 23 moved by a spring 24 into engagement with an upstanding post 25 on arm 15. As is usual in the "Sundstrand" adding machine, an upper push rod 26, operated by each digit key, releases arm 23 from post 25 to permit spring 20 to move arm 15 clockwise to bring the push rods 13 into alignment with the next line of stops 11.

In the "Sundstrand" adding machine, the pins 11 representing "0" are not normally set to active position and when a constant factor is to be indexed as above set out, all "0" pins 11 to the right of the last indexed pin 11 must be set to active position. For this purpose, each pin of the bot-

tom layer of pins 11 is provided on its lower side with a stud 29. Mounted on a bracket 30 slideable on a fixed rod 31, which bracket is a part of the entering mechanism 9 and is pivotally connected to arm 15, is a lever 32. Lever 32 is formed with a cam nose 33 on one end which cam 33 is normally positioned clear of studs 29 on the lower pins 11 and carries a stud 34 fixed in its other end, see also Figure 3. A spring 35 secured between bracket 30 and lever 32 and a detent 36 on bracket 30 urged counterclockwise by a spring 37 serve to retain lever 32 in its normal position.

When the last significant figure of a constant factor has been entered and the remainder of the denominational orders are to have "0's indexed therein, a special key 40 adjacent the normal "0" key 14 is depressed. Depression of this key rocks a bell crank 41 pivoted on a bracket 42 fixed to base plate 17 to thrust a link 43 rearwardly and rock arm 44 counterclockwise. Arm 44 is pivoted at 45 to plate 17 and carries a stud 46 engaged with a slide 47 slideable on a stud 48 in arm 15 and urged forwardly by a spring 49. The rear end of slide 47 lies in front of an extension of lever 32 and when slide 47 is moved rearwardly by depression of key 40 through link 43 and arm 44, it rotates lever 32 counterclockwise to an active position. Spring 49 restores the slide 47 and the key 40 to normal position upon release of pressure on key 40 but lever 32 remains in its set position since its stud 34 has been moved into the forward notch of detent 36. In its movement to set position cam nose 33 of lever 32 has engaged stud 29 of the pin 11 in alignment therewith and has set the pin to active position.

After lever 32 has been set to active position or concomitantly therewith, escapement arm 23 is moved to an ineffective position to permit a free movement of arm 15 by spring 20 to the rightmost position. Such releasing of escapement arm 23 is under control of a constant key 52, Figure 1. This constant key 52 is the same key as key 90 in the Swanson et al. application, Serial No. 182,672, supra, with the exception that the interlock nose 104 and the cooperating end of lever 91 of Figure 1 of said application have been omitted as unnecessary.

Briefly the escapement release mechanism comprises the constant key 52 which is pivoted on a stud 50 in a lever 53 rotatable on a stud 51 in the right wall 54 of the keyboard. A spring 55 connected to the forward end of lever 53 serves to maintain the key 52 and lever 53 in a normal position. The upper end of lever 53, Figure 2, is connected to an arm of a bell crank 56 which carries a latch 57 for a slide 58 urged rearwardly by a spring 59. A connecting arm 60 is pivoted on slide 58 and normally rests in front of a square stud 61 on escapement arm 23. Depression of key 52 will through levers 53 and 56 release latch 57 from slide 58 which will then be moved rearwardly by a spring 59 and through arm 60 move square stud 61 rearwardly. Such motion of stud 61 rocks escapement arm 23 counterclockwise in Figure 2 to release it from post 25 of arm 15. Arm 15 will then move freely to its rightmost position. During the following machine cycle, slide 58 is restored to normal latched position by a power operated arm 62 as described in the above Swanson et al. application.

It will be recalled that lever 32 on bracket 30 has been previously set to active position by operation of the multi-zero key 40. During the movement of arm 15 and bracket 30 connected thereto when released by depression of constant key 52, cam nose 33 of lever 32 wipes across the

studs 29 of all of the "0" pins 11 to the right and sets these pins to active position thus indexing "0" in all remaining denominational orders.

The width of cam nose 33 is slightly greater than that of the ends of push rods 13 with the extra width to the right side. Consequently, the rightmost "0" pin 11 will be set before the arm 15 has fully moved into the end position. The short remaining movement of arm 15 is used to release lever 33 for return to its inactive position. Detent 36 has its forward end bent upwardly to a point above the depressed forward end of lever 32. A stationary release arm 65 is fixed to the right hand side of the pin carrying frame 12 and extends leftward between the lowest row of pins 11 and the path of the forward depressed arm of lever 32. After cam nose 33 has set the last "0" pin 11 to the right and during the short remaining movement of bracket 30, the release arm 65 strikes the forward end of detent 36 to cause clockwise rocking of said detent and consequently release of lever 32. Spring 35 connected to lever 32 thereupon restores the lever to its normal ineffective position in readiness for further operation. When swinging arm 15 is restored one or more steps toward the left, detent 36 is freed from the release arm 65 and is again effective to retain lever 32 in a set position.

It will be now evident that the multi-zero indexing mechanism above described when operated, will index a zero in all non-indexed orders of pins and does not index a fixed number of zeros thus requiring a separate key for each different number of zeros and a plurality of key operations to locate the indexing mechanism at the full capacity position.

The above description of a preferred embodiment of my invention is illustrative only and is not to be taken in a limiting sense as many variations thereof are possible within the scope of the following claims.

What is claimed is:

1. In an adding machine or the like, having a plurality of lines of normally non-indexed settable stop pins to control amount entering operations of said machine, a plurality of manually operable stop pin setting members relatively shiftable across said stop pins, spring means to relatively shift said stop pins and said setting members to present successive lines of said stop pins to said setting members and an escapement device to restrain such relative shifting means, the combination of a member relatively shiftable with said stop pin setting members, key operable means to set said member from an ineffective position to a position wherein it will engage portions of certain of said stop pins and thereby set said certain pins during said relative movement, and means to release said escapement device to free said stop pin setting members and said member shiftable therewith for relative movement with respect to said stop pins.

2. In an adding machine or the like, having a plurality of lines of indexable stop pins to control value entering operations of said machine, a plurality of manipulative stop pin indexing members and means to relatively shift said stop pins and said setting members to bring said indexing members into operative relationship with successive lines of stop pins, a member relatively shiftable with said indexing members and normally in a non-engaging position with respect to said stop pins, manual means to set said member to an indexing position wherein said member will index one of said stop pins in each line trav-

ersed during such relative shift, detent means to hold said member in said set position, means operable to control said shifting means to cause an uninterrupted relative shift of said indexing members and said stop pins to the full extent of said relative movement and means operative at the end of said relative shifting movement to release said detent from said member and enable restoration of said member to the non-engaging position.

3. In an adding machine or the like, having a group of settable index pins arranged in rows, a plurality of manipulative members operable to set said index pins to a position to control amount entering operations of said machine and relatively shiftable into alignment with successive rows of said group of index pins, a member movable with said plurality of manipulative members and operable to set the adjacent index pin representing a zero, means to retain said member in an operated position, manual means to operate said member to an index pin setting position, a constant key, means operable thereby to determine relative shifting of said plurality of members to an end position with respect to said group of index pins, said member, when in the operated position, acting during said relative shifting movement to set the index pin representing zero in each row traversed during such relative shift, and mechanism operative at said end position to release said holding means from said member to enable restoration of said member to a non-indexing position.

4. In an adding machine or the like, having a plurality of settable index pins arranged in denominational orders, pin setting members relatively denominational shiftable across said index pins, power means to shift said pin setting members relative to said index pins and escapement mechanism to restrain said members against the action of said power means and in alignment with any denominational order of said index pins, a cam member shiftable across said plurality of index pins with said pin setting members, means operable to set said cam member from a normal ineffective position into an effective pin setting position with respect to one index pin in each denominational order, whereby said one index pin in the aligned denominational order is set, detent means to retain said cam member in the set position, a normally latched spring urged means operable when unlatched to release said relatively shiftable pin setting members and said cam members from restraint by said escapement mechanism whereupon said power means is effective to shift said pin setting

and cam members to an end position, a latch for said spring urged means, a manually operable key to release said latch from said spring urged means, said cam member when in the effective position acting during the resultant relative shift of said index pins and said pin setting members to set said one index pin in each denominational order passed over and a stop fixed with respect to said plurality of index pins to engage said detent means at the end of such relative movement and release said detent from said cam member to enable restoration of said cam member to the normal position.

5. In an adding machine or the like, having a plurality of settable index pins arranged in denominational orders, said pins representing values from "0" to "8" in each order, manipulative pin setting means shiftable into alignment with successive denominational orders of said index pins, power means urging said manipulative pin setting means in one direction, and escapement mechanism to restrain said manipulative pin setting means against movement and operable by said manipulative means to permit advance of said manipulative means to the succeeding denominational order, normally latched spring driven means to disable said escapement mechanism and free said manipulative pin setting means for movement by said power means to an end position, a latch for said spring driven means, a constant key operable to release said latch from said spring driven means, a cam member movable by said power means in synchronism with said manipulative means, a key to set said cam member into a pin setting position with respect to the index pins representing "0," a detent to hold said cam member in such pin setting position and an arm operative to release said detent from said cam member when said manipulative means is in said end position.
